US0D1100926S

(12) **United States Design Patent** (10) Patent No.: **US D1,100,926 S**
Dry et al. (45) Date of Patent: ** Nov. 4, 2025

(54) **DISPLAY SCREEN OR PORTION THEREOF WITH GRAPHICAL USER INTERFACE**

(71) Applicant: **Invanti, Inc.**, South Jordan, UT (US)

(72) Inventors: **Anthony Dry**, Daresbury (GB); **Mark Tempel**, New Brighton, MN (US); **Oliver Sills**, Daresbury (GB)

(73) Assignee: **Invanti, Inc.**, South Jordan, UT (US)

(**) Term: **15 Years**

(21) Appl. No.: **29/919,160**

(22) Filed: **Dec. 1, 2023**

(51) LOC (15) Cl. **14-04**

(52) U.S. Cl.

(57) **CLAIM**

The ornamental design for a display screen or portion thereof with graphical user interface, as shown and described.

DESCRIPTION

FIG. 1 is a front view of a display screen or portion thereof with graphical user interface showing our new design; FIG. 2 is a front view of a second embodiment thereof; and, FIG. 3 is a front view of a third embodiment thereof. The outermost broken line in all views is an environmental feature illustrative of a computer display screen or portion thereof and forms no part of the claimed design. The remaining broken lines illustrate parts of the graphical user interface and form no part of the claimed design.

1 Claim, 3 Drawing Sheets
